UNITED STATES PATENT OFFICE.

JAMES M. ROBBINS, OF CAMDEN POINT, MISSOURI; ANNA ROBBINS ADMINISTRATRIX
OF SAID JAMES M. ROBBINS, DECEASED.

APPARATUS FOR DISTRIBUTING INSECTICIDES.

Application filed June 9, 1927. Serial No. 197,672.

This invention relates to apparatus for distributing insecticides and more particularly to a bellows structure adapted for use in this connection.

An important object of the invention is to provide a bellows construction in which the hinge is formed by the flexible wall forming element of the bellows and is so arranged that it may be shifted in event the wall structure becomes dangerously worn, so that it is liable to cause leakage.

A further object of the invention is to provide a device of this character of such construction that the delivery of an excessive amount of the insecticide is prevented.

A further object of the invention is to produce a device of this character which may be readily and cheaply manufactured, which will be durable and efficient in service and a general improvement in the art.

These and other objects I attain by the construction shown in the accompanying drawing, wherein for the purpose of illustration is shown a preferred embodiment of my invention and wherein:—

Figure 1 is a plan view of an insecticide distributor constructed in accordance with my invention;

Figure 2 is an enlarged sectional view on the line 2—2 of Figure 1;

Figure 3 is a detail sectional view on the line 3—3 of Figure 1, the dotted lines indicating the reversed position of the plate.

Referring now more particularly to the drawing, the numeral 10 generally designates rigid bellows walls, one of which is provided with an opening 11 through which the insecticide may be inserted to the interior of the bellows. These rigid walls are provided with the usual operating handles 12 and are provided about their edges with a wall 13 of tough flexible material, such as leather. The strip from which this wall 13 is formed is preferably overlapped at the smaller ends 14 of the rigid walls 10 so as to produce a double thickness and at the center of the end wall 15 thus produced, openings are formed through the overlapped edges of the strip. Mounted upon the inner face of the aligned opening 16 is a plate 17 having rigidly secured thereto the central portion of a conduit 18, the outer end of which projects beyond the outer face of the wall 15 and the inner end of which

communicates with the center of a substantially U-shaped conduit 19, the ends of the arms of which are extended toward the wall 15.

Secured to the outer face of one of the side walls 10 is a plate 20 having an angular flange 21 opposing the end wall 15 and provided with an axial opening 22 through which the tube 18 extends. Arranged at the inner face of the flange 21 is a pressure plate 23, which actually abuts the wall 15 and which is held in engagement therewith by securing elements 24 carried by the plate 17 and extending through the wall 15, flange 21 and plate 23. The flange 21 and plate 23 are held in position by nuts 25 mounted upon these securing elements and by removing these nuts and the screws 26 holding the plate 20 to the side wall 10 and securing the plate 20 to the opposite side wall, the position of this plate may be reversed. Since the plate 23 and the plate 17 serve to clamp the wall 15 rigidly to one of the side walls 10, it will be obvious that between the edge of this plate and the other of the side walls, a hinge will be formed providing the pivot, permitting relative movement of these side walls to produce the bellows axle. By reversal of the plate, this hinge is shifted from one edge to the other of the wall 15, so that when one edge of the wall becomes worn, the other edge thereof can be employed as a hinge, thus materially increasing the life of the article.

It will be obvious that in operation of a device of this character, there is a tendency to formation of an air current starting from the larger ends of the bellows walls and moving toward the smaller end thereof. Because of this movement of the air current, insecticides placed within the bellows have a tendency to move toward the smaller end and choke the outlet or pass therefrom in excessive quantities. By the use of the conduit 19, the ends of which are directed toward the smaller end, this choking tendency is prevented and a smooth distributing operation provided. The outer end of the conduit 18 has preferably detachably connected therewith a funnel-shaped spreader nozzle 27. Secured to each rigid bellows wall 10, adjacent the end wall 15, is a plate 28 which has openings therethrough corresponding to the openings of the plate 20 and which ac-

cordingly serves to reinforce the securing elements of the plate 20 in its applied position. Each plate 28 has a flange 29 abutting the corresponding edge of the end wall 5 15 and serving to reinforce the connection of the end wall to the ends of the rigid bellows walls 10.

Since the construction hereinbefore set forth is capable of a certain range of change 10 and modification without materially departing from the spirit of the invention, I do not limit myself to such specific structure except as hereinafter claimed.

I claim:—

- 15 1. An insecticide distributor comprising a bellows having a discharge conduit extending into the interior thereof through the hinge wall of the bellows and communicating at its inner end with a conduit the terminal portions of which are directed toward said wall.
- 20 2. In an insecticide distributor, a bellows structure, a discharge conduit for the bellows extending into the bellows through the hinge wall thereof and a U-shaped conduit with which the inner end of the discharge conduit communicates at the connection between the arms thereof, the free ends of said arms being directed toward said hinge wall.
- 25 3. A bellows structure comprising opposed rigid side walls, a strip of tough flexible material connecting said walls, the ends of the strip being overlapped at one end of the rigid walls, a plate securable to either of said rigid walls having a flange opposing and rigidly secured to said overlapped portions to rigidify them to the wall to which said plate is secured, the end of said flange 30 extending adjacent the other of the rigid walls.
- 40 4. A bellows structure comprising opposed

rigid side walls, a strip of tough flexible material connecting said walls, the ends of the strip being overlapped at one end of the rigid walls, a plate securable to either of said rigid walls having a flange opposing and rigidly secured to said overlapped portions to rigidify them to the wall to which said plate is secured, the end of said flange extending adjacent the other of the rigid walls, a plate at the interior of the bellows and opposing the inner face of the overlapped portions of the strip, a conduit rigidly secured to said plate and extending through openings formed in said overlapped portions and said flange and means rigidly connecting said plate and the flange of the first named plate.

5. A bellows structure comprising opposed rigid side walls, a strip of tough flexible material connecting said walls, the ends of the strip being overlapped at one end of the rigid walls, a plate securable to either of said rigid walls having a flange opposing and rigidly secured to said overlapped portions to rigidify them to the wall to which said plate is secured, the end of said flange extending adjacent the other of the rigid walls, a plate at the interior of the bellows 65 and opposing the inner face of the overlapped portions of the strip, a conduit rigidly secured to said plate and extending through openings formed in said overlapped portions and said flange, means rigidly connecting said plate and the flange of the first named plate, a U-shaped conduit with which the inner end of said conduit communicates at the center thereof, the ends of the arms of the U-shaped conduit being directed toward 70 the last named plate.

In testimony whereof I hereunto affix my signature.

JAMES M. ROBBINS.
